CATAMARAN HULL

Dwight E. Woolever, Los Angeles, Calif.

Application July 8, 1957, Serial No. 46,866

Term of patent 14 years

(Cl. D71—1)

Fig. 1 is a side elevational view of a catamaran hull showing my new design;

Fig. 2 is a central longitudinal sectional view thereof;

Fig. 3 is a bottom plan view;

Fig. 4 is a front elevational view of the catamaran hull; and

Fig. 5 is a rear elevational view thereof.

I claim:

The ornamental design for a catamaran hull, substantially as shown.
